ADVERTISING SIGN.

No. 16,984.

Patented Nov. 16, 1886.

UNITED STATES PATENT OFFICE.

ARTHUR D. GIANNINI, OF NEW YORK, N. Y.

DESIGN FOR AN ADVERTISING-SIGN.

SPECIFICATION forming part of Design No. 16,984, dated November 16, 1886.

Application filed September 28, 1886. Serial No. 214,805. Term of patent 7 years.

To all whom it may concern:

Be it known that I, ARTHUR D. GIANNINI, a citizen of the United States, residing at New York, in the county of New York and State of New York, have invented and produced a new and original Design for Advertising-Signs, of which the following is a specification, reference being had to the accompanying illustration, forming a part thereof, which is a representation of my newly-designed advertising-sign.

This sign was designed especially as an advertisement for breweries; and to that end the leading feature of the design consists in the representation in relief of a barrel-top on an ornamental shield, the barrel-head being adapted to receive the advertising words, characters, or symbols in relief or otherwise. The ends of the barrel staves project an inch or so above the barrel-head, which is in this case of oval form, and thus form an inclosure, within which the advertisement is produced. The shield is ornamented at the sides and top with scrolls of graceful design, the whole being in relief, and on the ornamental scrolls on the shield, at either side of the barrel-top, are perched two eagles partially concealed by the shield. On the crest of the shield, and directly above the ornamental double scroll produced in relief above the barrel-top, is arranged a cluster of hop berries and leaves, together with a portion of the vine bearing them, also in relief, and among the branches of the double scroll at the foot of the shield are entwined the bunched stalks of two crossed sheaves of barley in basso-rilievo. On the barrel-head are produced in relief the words, symbols, &c., constituting the advertisement proper; but such matter constitutes no part of my design.

I claim—

1. The design for an advertising sign herein shown and described, the same consisting of the representation of the top of a barrel upon a shield, and an eagle or eagles perched adjacent to the said barrel-top. 40
2. The design for an advertising sign herein shown and described, the same consisting of the representation of the top of a barrel upon an ornamental shield, and eagles perched upon the shield. 45
3. The design in relief for an advertising-sign herein shown and described, the same consisting of the representation of a barrel-top on an ornamental shield, eagles perched at the side of the shield, a cluster of hop leaves and berries on the crest of the shield, and sheaves of barley at the foot of the shield. 50
